SHOWER PIPE

Filed Aug. 1, 1929

FIG 1

FIG 3

FIG 2

INVENTOR

BY Paul H. Mielke
M. S. Babcock

ATTORNEY

UNITED STATES PATENT OFFICE

PAUL H. MIELKE, OF SANDUSKY, OHIO, ASSIGNOR TO THE PAPER & TEXTILE MACHINERY CO., OF SANDUSKY, OHIO

SHOWER PIPE

Application filed August 1, 1929. Serial No. 382,629.

The invention to be hereinafter disclosed relates to shower pipes for paper making machines.

Shower pipes of this general class are used for spray-washing in continually showering the rapidly moving making-wires, felts and various other parts of the paper making machines to keep them free from adhering fibres and foreign substances contained in the pulp.

For economical and efficient cleansing of paper making machinery it is essential to shower the parts to be cleansed with an unbroken and forceful sheet of liquid. The most universally used and recognized type of such shower pipes is disclosed in the Millspaugh shower pipe Patents 782,680 and 782,755, both granted February 14, 1905, together with his earlier Patents 596,939, 596,940 and 596,941, granted January 4, 1898, which latter three have been considerably displaced by the two first mentioned. In each of these examples a continuous sheet of the cleansing liquid is obtained by a discharge pipe having a line of orifices and provided with suitable nozzles, deflecting lips or planes angularly disposed to the actions of the issuing jets or streams which infringe on said lips or planes and thence discharge in thin sheets having diverging sides, the outer edges of which sheets all meet at the same line to form a continuous, unbroken sheet. The sizes and distances between the orifices or discharge ports and their positions relative to their deflecting planes determine the line at which the several streams meet, and the shower pipe is preferably so located with relation to the parts to be cleansed as to cause such meeting-line to lie on or approximately on the surface to be showered.

In the earlier patents referred to, the deflecting lips or planes are adjustable, relatively to the pipe, such adjustability being circumferential. There were objections to this type of adjustment and the later patents were made with rigid, fixed, or stationary deflectors. But, in the mills of the present time a considerably higher water pressure is used than in the earlier years of these later Millspaugh patents. The result is that in localities where there is any foreign matter in the

water the deflecting plate becomes grooved at points where the jets issuing from the perforations first strike. As soon as a groove starts, the otherwise fan-shaped sheet formed by that particular jet correspondingly narrows. The result is, instead of one continuous sheet, at the line where water and wire or felt meet, there is a plurality of separate narrow sheets with intervening gaps. Thus, as soon as grooves start to appear, the continuous sheet is reduced to a number of separate narrow sheets which spray or wash corresponding strips or bands of the wire or felt, leaving intervening unwashed bands.

The main object of the present invention is to avoid this serious defect and provide a light, strong, efficient and economical shower pipe in which the deflector plate may readily and easily be adjusted to compensate for the grooving tendency, or easily and quickly completely be removed for renewal, when that becomes necessary.

To this end my invention consists, broadly, of a shower-pipe having a longitudinal line of discharge-ports and closely adjacent thereto a deflecting plate or lip formed separately therefrom but longitudinally, slidably, keyed thereto in position to intercept and deflect in a single continuous sheet the several separate jets issuing through the discharge-ports.

In order to more clearly disclose the construction, operation, and use of the invention, reference should be had to the accompanying drawings forming part of the present application. Throughout the several figures of the drawings like reference characters indicate the same parts in the several views.

In the drawings:

Fig. 1 is a side elevation of a pipe with the invention applied;

Fig. 2 is an enlarged cross section at right angles to the longitudinal axis and

Fig. 3 is a view similar to Fig. 2, showing a slight modification.

Referring to the drawings in detail, 95
1 indicates the body of the pipe suitably mounted in well known manner and provided with any desired connection to a supply of water under pressure. This pipe is drawn or otherwise worked to provide a longitudinally 100

exending dove-tail tongue or rib 2. Adjacent to the dove-tail 2 but slightly spaced therefrom, circumferentially, is a row of discharge-ports or jet openings 3. These perforations are radially disposed and are of such diameter and relative disposition as to make it possible, with the aid of the deflecting plate to convert the several jets into a single continuous sheet along a predetermined line.

Slidably mounted on said dove-tail rib 2, and having a snug fit therewith is the deflector plate 4 having the dove-tail channel or groove 5 complementary to and receiving said rib. The metal of the channel piece has a slight degree of spring or yield as shown at 6. Thus should the fit be tighter than desirable the plate will spread, slightly and prevent binding. Likewise, the edges of the channel portions of the plate do not both fit snugly and tightly into the opposite angles of the rib or tongue. If one edge makes a snug fit the other is slightly loose, as clearly shown. Preferably, the one along the side opposite the perforations is the looser one. Should the other one be the looser, water might work back from the perforations and between the rib and plate and cause rust or deposit and binding. It would also break the spray and destroy the continuity of the sheet at this point. It will be noticed that the dove-tail tongue and groove, as formed in this case, has no sharp angles. Wherever there would be a sharp angle there is, instead, a gradual curve or rounded surface to, as nearly as practicable, entirely eliminate all binding at such points.

The operative part of the deflector plate is so inclined, positioned and directed with respect to the jet openings as to intercept the jets, spread them into one continuous sheet, and when the spray pipe is properly mounted in its machine, deliver that sheet against the wire felt or other part, at the point desired.

While the sliding fit between plate 4 and rib 2 is not loose neither is it tight. It is a snug fit and the plate may be moved longitudinally, in either direction, by a moderate tap on one or the other end. Thus when any evidence of grooving appears it is only necessary to tap the plate end until it is moved a distance equal to the diameter of one of the perforations, or very slightly more, thereby bringing into operation an entirely fresh and unused plate surface for every jet. When all parts of the plate have been used or, for any other reason a new plate is desired, it may be simply drawn off and a new one substituted.

Obviously, plates of different inclination or design or otherwise different may be similarly substituted when desired.

Preferably, the rib 2 is die-formed by reducing the diameter of the tube or pipe. To more readily get the dove-tail form a rod 7 may be used, being held in the fold of the

tube and thereby forcing the same into the fan or dove-tail form. This modification is clearly shown in Fig. 3.

It is thought that the construction, operation and use of the invention will be clear from the preceding detailed description wherein only a preferred form has been disclosed by way of illustration.

Having thus described my invention, what I claim and desire to protect by Letters Patent is:—

1. In a sprinkler pipe for paper making machines, a pipe body provided with jet openings and a deflector plate mounted thereon and adapted to be adjusted longitudinally thereof.

2. In a sprinkler pipe for paper making machines, a pipe body provided with jet openings and having a rib adjacent said openings, and a deflector plate carried by said rib adjacent said openings and adapted to be adjusted longitudinally of said rib.

3. In a sprinkler pipe for paper making machines, a pipe body provided with jet openings and having an integrally formed rib adjacent said openings, and a deflector plate carried by said rib adjacent said openings and adapted to be adjusted longitudinally of said rib.

4. In a sprinkler pipe for paper making machines, a pipe body provided with jet openings and a deflector plate adjacent said openings and longitudinally slidably mounted on said pipe body.

5. In a sprinkler pipe for paper making machines, a pipe body provided with jet openings and a dove-tail rib adjacent said openings, and a deflector plate adjacent said openings and provided with a channel complementary to said rib and adapted to slidably receive the same.

6. In a sprinkler pipe for paper making machines, a pipe body provided with jet openings and a dove-tail rib adjacent said openings and a deflector plate adjacent and complementary to said rib, said plate and rib having sliding functional engagement whereby the plate may be adjusted longitudinally of the rib and will retain its selected position of adjustment.

In testimony whereof I affix my signature.
PAUL H. MIELKE.
